TILING AND THE LIKE

George H. Lenke, Elmhurst, Ill., assignor of one-half to Julius J. Ohlis, Oak Park, Ill.

Application September 28, 1933, Serial No. 691,293

8 Claims. (Cl. 72—19)

My invention relates to tiling and the like, and contemplates an improved tiling system in which the tiling is applied and secured in place without cement or exposed metal parts; a tiling system that may be installed rapidly and inexpensively; a tiling system in which the tiles are locked in place by attaching members secured to the desired wall or other surface and concealed from view when the tiles are applied; a tiling system in which it is unnecessary to grind the edges of the tiles to give even joints as has been the case where the tiles have been cemented in place; a tiling system in which the finished surface is smooth and easily cleaned; a tiling system that may be installed in a simple manner; a tiling system which eliminates the necessity and labor of providing a plastic bonding on the wall, ceiling or other surface; a tiling system which is self-centering and self-squaring; a tiling system having attaching members of spring-like character whereby the tiles are protected to a large extent from breakage or disalignment due to vibration or settling of the building structure; a tiling system which, when applied, presents an outer surface having no visible means of attachment; and a system having a replacement method and parts for replacement of broken tile.

The tiling system which I shall describe hereinafter, in connection with the drawings, is adapted for use on bathroom and kitchen walls and ceilings, or on any other wall, ceiling or surface as suitable or desired.

The tiling system of my present invention may be used with glass tiles, which may be molded, pressed or otherwise formed, and it may be used with tiles, panes or panels of composition such as "bakelite", "micardo", or any other suitable or preferred material.

The number of tiles, panes or panels, as well as the shapes and proportions of the panels, and the shape and proportion of the structure in its entirety may vary according to the particular installation or use to which the invention is put, and the appended claims are to be construed accordingly.

Now, in order to acquaint those skilled in the art with the construction of the parts and the manner of applying the tiling therewith, I shall describe certain specific embodiments of the invention in connection with the accompanying drawings, in which:

Figure 1 is a fragmentary elevational view of a tiling system embodying my present invention showing the manner of applying the tiles;

Figure 2 is an enlarged fragmentary vertical section;

Figure 3 is a fragmentary perspective view;

Figure 4 is a fragmentary detail section;

Figure 5 is a view similar to Figure 1 showing another embodiment of the invention;

Figure 6 is a perspective view, partially broken away, of one of the tile members employed in the embodiment of Figure 5; and

Figure 7 is a fragmentary perspective view showing one of the attaching members of Figure 5 and the manner of securing the tile members to the wall or other surface therewith.

It is to be understood that where I refer herein to certain members as vertical members and other members as horizontal members, this has reference merely to the particular arrangement illustrated in the drawings, and the disposition of these members may be reversed or otherwise varied from that shown and described without departing from the spirit and scope of my present invention.

Referring first to Figures 1 to 4, inclusive, the structure therein illustrated comprises generally the vertical attaching members 5, tile members 6 and spacer members 7.

The attaching members 5 are formed of metal. Each has an outstanding T-shaped tongue or tenon 9 comprising a neck 10 flanged outwardly from opposite sides of its outer end to provide the flat head 11, the sides of which are engageable in vertical grooves 12 in the opposite vertical edges of adjacent tiles 6 to lock the tiles securely in place upon the wall or surface 13. At opposite sides of the head 11, the metal forming the member 5 is turned in at 14 toward the center of the head 11 where the inturned portions are brought together and turned at right angles to form the neck 10. The inner ends of the inturned neck forming portions are turned outwardly at 15 to form the base part, and the outwardly turned base forming portions 15 terminate along their outer margins in generally V-shaped tile seating portions 16. The obliquely disposed wings formed by the V-shaped portions 16 present along their outer margins, edges 18 for line contact with the back sides of the tile members 6.

The attaching members 5 may be formed of sheet metal pressed to shape, or they may be formed to shape by rolling, drawing, casting, molding, extruding, or otherwise as desired, depending, in many instances, upon the particular material selected for use. Each of these members 5 preferably has some springiness as, for example, by making the members of suitable spring metal.

This springiness with the formation of the V-shaped portions 16 gives the seating wings the desired spring-like character. The spring-like action of these tile seating portions holds the tile members in place without looseness and, at the same time, protects the tile members to a large extent from breakage or disalignment due to vibration or settling of the building structure. The members 5 may be galvanized if and as desired.

The tile members 6 may be formed of glass molded, pressed, or otherwise brought to the desired form, or they may be formed of compositions such as "bakelite" or "micardo," or of any other suitable or preferred material. In the illustrated embodiments, the tile members are of generally square flat formation, but they may be elongated and of other forms as already pointed out. In the embodiment of Figures 1 to 4, each piece of tile 6 has the groove 12 extending through the entire length of each of its opposite vertical edges 21, and each of the horizontal edges 22 of each tile has a groove 23 extending throughout the length of the same, for a purpose which will presently appear.

Between the horizontal edges of the tile members 6 are disposed the spacer members 7. These spacer members 7 are formed of metal, preferably sheet metal, similar to the attaching members 5, and the material and formation of the members 7 may be varied in the manner of the variations referred to in connection with the attaching members 5. Each is of generally T-shaped form having the neck 25 flanged outwardly from opposite sides of its outer end to provide the flanged or flat head 26, the sides of which are engageable in the horizontal grooves 23 in the edges 22 of adjacent tiles to lock the tiles securely in place upon the wall or surface 13. At the opposite sides of the head 26, the metal forming the members 7 is turned in at 27 toward the center of the head 26 where the inturned portions are brought together and turned at right angles to form the neck 25.

The inner tongues 28, along the mortises or grooves 23 in the horizontal edges of the tiles 6, may be somewhat shorter than the outer tongues 29 to accommodate the necks 25 of the spacer members 7 without undue separation at 30 between the edges 22 of the tiles. Similarly, the inner tongues 32, along the mortises or grooves 12 in the vertical edges 21, may be shorter than the outer tongues 33 to accommodate the necks 10 of the attaching members 5 without undue separation at 35 between the outer edges 21 of the tiles. Cement or other suitable plastic material 36 may be employed for pointing the joints between the outer vertical edges 21 and the outer horizontal edges 22.

The means for securing the attaching members 5 to the rough wall, ceiling, or other surface 13, are indicated at 38. In the illustrated embodiment, these securing means 38 are in the form of nails driven through openings in the base portions 15 into the wall, ceiling, or other surface, and headed at their outer ends for cooperation with the base portions 15 of the member 5. Wood screws may be employed instead of nails, particularly in application of the tiling to a ceiling, and the screws may be secured to the stud strips or other suitable part of the wall, ceiling, or other surface. Other manners of and means for attaching the strips or members 5 to the desired surface may, of course, be employed.

In fact, the particular form of attaching means

will be governed by the type of surface and the material to be attached thereto.

Erection or installation is as follows:

The lower ends of the attaching members 5 are first nailed, screwed, or otherwise secured to the wall, ceiling, or other surface 13, or to the studding or framing therefor, in parallel spaced relation to receive and lock the tile members 6 in place. In the case of a wall or other vertical surface, these members 5 are preferably arranged vertically, as shown, although it is to be understood that they may be arranged horizontally or otherwise as desired.

The lower or first tile members 6 are then interlocked with the flanges or heads at the outer ends of the tongues or tenons 9 and are slipped into place. These lower or first tile units 6 may be squared and leveled, and thereafter the construction is self-centering and self-squaring. The attaching members 5 are secured in place and the tiles 6 applied thereto, preferably in alternate progression, the attaching members being preferably secured or fastened in place distances of about one or two tiles ahead of the application of each tile. This leaves the attaching members 5 above the tiling as it is built up on the wall free so that they may be spread as shown, for example, at 40 in Figure 1, to receive the tile members which are then slipped downwardly to position adjacent the previously applied tile. This eliminates the necessity of slipping the tile members into place from the extreme upper ends of the members 5.

Where the spacer members 7 are employed, they are applied to the upper edges of the tiles 6 and between the pairs of attaching members 5, preferably after application of the lower tiles and before applying the tiles which overlie the same. In other words, the tiles 6 and spacers 7 are set up alternately between the attaching members 5 with the flanges or sides of the heads 26 of the spacers in interlocking engagement with the grooves or mortises 23 in the horizontal edges of the tiles. The length of each spacer 7 is equal to the distance between the heads 11 of the attaching members 5, and their opposite ends abut the opposing edges of the heads or flanges 11 and space the members 5. The construction is thus self-centering and self-squaring and assures a uniformly pleasing, smooth and regular appearance when the tiling is completed. The spacers 7 may be omitted if desired, in which case the tiles may be set up directly upon one another vertically. In such case, the cooperating upper and lower edges of the tile members may be provided with cooperating mortises and tenons for interlocking and joining the same together, although this, too, may be omitted.

The pointing of the joints with cement or other suitable plastic material at 36 may be done after completing the erection or installation of the tiling, or it may be done as the tiling is installed. The finished surface is smooth and without visible means of attachment, the attaching members 5 and spacers 7 being obscured or concealed by the tile members 6.

Where the tiling is applied up to a corner, the upper tiles may be applied by flexing the strips 5 outwardly from the wall and apart to receive the tiles, and when the tiles are applied, flexing these strips back against and securing same to the surface 13. The strips 5 may be extended above the tiles for purposes of attachment, and the extending ends may be covered as suitable or desired.

For the purpose of replacing broken tile, or tile which for any other reason it is desired to replace, I provide a special replacement tile and attachment means therefor, as shown in Figure 4. This replacement tile 6' is formed of glass or other material corresponding to the material of the tile 6 which it is to replace, and is shaped and dimensioned to conform with the shape and dimensions of the tile 6. The grooves 12' correspond with the grooves 12 of the tile 6, and the outer tongues 29', along said grooves, correspond with the outer tongues 29 of the tiles 6. The inner tongues 28' are shorter than the inner tongues of the tiles 6 to provide space and clearance for the attaching members 42.

The attaching members 42 have U-shaped portions 43 fitted around the tongues 28' with the outer folded sides 44 of the U-shaped portions fitting in the grooves 12', and the inner folded portions 45 fit around the inner sides of the tongues 28'. The inner side of each folded portion 45 has an extension 46 turned outwardly toward the front of the tile and normally lying obliquely, as shown at the left hand side of Figure 4. The oblique extension 46 has springiness which permits it to be pressed toward the base of the U-shaped portion by engagement with the head 11 of the attaching member 5 in applying the tile 6'.

Assuming that one of the tile members 6 has been broken and that it is desired to replace the same, the broken parts are removed and the replacement tile 6', with its attaching members 42 in place, is brought to position and pressed into the opening from which the broken tile has been removed. This pressing of the replacement tile into place causes the extensions 46 to engage the head 11 and to be pressed thereby toward the bases of the U-shaped portions 43. This permits the extensions 46 to clear the head or flange 11, and as these extensions move to position rearwardly of the head 11 and the back of the tile into engagement with the edges 18 of the tile seating portions 16, the extensions 46, due to their springiness, spring out to oblique position and into cooperation with the inner sides of the heads 11, as shown to the left in Figure 4, thereby locking the replacement tile securely in place behind the flanges of the original attaching members 5.

The attaching members 42 may be provided along the vertical and horizontal edges of the replacement tiles 6', or, if desired, they may be provided only along the vertical edges. Where such members are provided along the vertical edges of the replacement tile the extensions 46 snap behind and interlock with the head or flanged parts 11, and where such members 42 are provided along the horizontal edges of the tile, the extensions 46 snap behind and interlock with the head or flanged parts 26 of the spacer members 1. Where members 42 are omitted along any one or plurality of the edges of the tile member, the relative short tongues 28' along such sides will clear the adjacent flanged or headed tenons in pressing the replacement tile into place.

In the embodiment of Figures 5, 6 and 7, the tile attaching members 60 are in the form of corner pieces occurring only at the corners of the tile members. As in the preceding embodiment, the tile members 61 may be formed of glass molded, pressed, or otherwise brought to the desired form, or they may be formed of "bakelite" or "micardo", or of any other suitable or preferred material. As before, they are of generally

square flat formation, but they may be elongated and of other forms as already pointed out.

The corner attaching members 60 are formed of metal, preferably of sheet metal having some springiness, although this may vary as in the preceding embodiment. Each has four outstanding T-shaped tenons 62 radiating ninety degrees apart from the center of the corner member. These tongues or tenons have neck portions flanged or headed at their outer ends at 63, as in the previous embodiment. The base portions 64 are turned out and nailed, screwed, or otherwise secured at 65 to the surface 66 or to the structure provided with such surface. The opposite margins of the base portions 64 are provided with tile seating portions 68 which preferably have some springiness and seat along their edges 69 against the back sides of the tiles 61 to hold the tile members in place without looseness and, at the same time, to protect the tile members to a large extent from breakage or disalignment due to vibration or settling of the building structure.

Each tile member 61 is grooved along the edges 10, 11, 12 and 13 at the corners only, as shown at 74. In erection or installation, one of the corner members 60, or the first row of corner members, are first nailed, screwed, or otherwise secured to the surface 66, or to the structure having such surface. The tile members are then applied with the grooves 14 in interlocking engagement with the flanged heads 63 of the tongues or tenons 62, whereupon corner members are applied to the other meeting corners of the tiles 61 and secured to the surface or structure 66. Further tiles are then applied, whereupon further corner members and tiles are alternately applied to build up the desired tile surface. It is to be understood that, particularly after the first corner member or first series of corner members are applied and the tile members interlocked therewith, the further corner members which are applied may be secured to the surface or structure 66 only along the exposed sides of the tenons 62. This provides adequate attachment and enables interlocking these corner members with the tiles and securing the same in place upon the surface or structure 66 after interlocking engagement with the previously applied tile members.

As before, the embodiment of Figures 5, 6 and 7 has the same advantages as the previous embodiment, except that in Figures 5, 6 and 7 the tile members act as their own spacers. The tiling is applied and secured in place without cement or exposed metal parts, although the joints between the tile members may be pointed with cement or other plastic material at 80. As before, the tiling is installed rapidly and inexpensively, and the tiles are locked in place by attachment members secured to the desired wall or other surface and concealed from view from the outer side by the tile members. It is unnecessary to grind the edges of the tile members to give even joints, the finished surface is smooth and easily cleaned, the tiles are protected to a large extent from breakage or disalignment due to vibration or settling of the building structure, and the necessity and labor of providing a plastic bonding on the wall, ceiling, or other surface, is eliminated.

Tiles which are broken or which, for any other reason, it is desired to replace, may be replaced in the manner of the previous embodiment. In such case, attaching members similar to the at-

taching members 42 of the previous embodiment may be applied to the tile members 61 along the grooved corners and in interlocking engagement with the grooves 74, and the oblique extensions 5 having the desired springiness may be snapped in behind the flanged heads 63 in pressing the replacement tiles into place. Such replacement attaching members may extend along the corners only of all four sides of the tile member, or 10 they may extend along only the corners of two opposite sides of the tile member if desired.

I do not intend to be limited to the details shown and described.

I claim:

15 1. In combination, tile attaching members, and tile members adapted to be interlocked with said attaching members by relative sliding movement thereof only and secured in place by the interlocking engagement with said attaching members, said attaching members having springiness to be spread apart for the introduction of said tile members into sliding interlocking engagement therewith and spacer members extending between and spacing said attaching members and 25 disposed between adjacent edges of said tile members.

2. In combination, a structure having a surface, a plurality of attaching members secured to said surface in parallel spaced relation, said 30 attaching members having springiness and each comprising a base portion for attachment to the surface, an outstanding flanged tenon, and obliquely disposed tile seating spring portions disposed on opposite sides of said tenon, and tile 35 members having grooved edges for interlocking with the flanged tenons of said attaching members and seating at their back sides on said tile seating spring portions, the attaching members being spreadable for introduction of said tile 40 members into interlocking engagement therewith.

3. In combination, a structure having a surface, tile members covering said surface, said tile members having grooved edges for a portion of their length only, and attaching members in the 45 form of corner pieces having flanged tenons co-operating with the grooves in the tile members for interlocking with the corners only of said tile members and secured to said structure.

50 4. In combination, a structure having a surface, tile members covering said surface, said tile members having grooved edges for a portion of their length only, and attaching members in the form of corner pieces having flanged tenons co-

operating with the grooves in the tile members for interlocking with the corners only of said tile members and secured to said structure, said attaching members being concealed by said tile members from view from the outer side of said tile members.

5. In combination, tile attaching members, and tile members adapted to be interlocked with said attaching members and secured in place by the interlocking engagement with said attaching members, said attaching members having springiness and provided with yieldable and angular tile seating wings disposed on opposite sides of the interlocking engagement with the tile members and cooperating with the back sides of said tile members to provide a yieldable seat therefor and normally to urge said tile members yieldingly into firm interlocking engagement with said attaching members.

6. As an article of manufacture, an attaching member for tiling and the like, said attaching member having a base portion for attachment to a support, said base portion being folded between its sides to form an outstanding tenon, said tenon being folded at its outer end to form a flanged head, and yieldable and angular tile seating wings disposed on opposite margins of said base portion for yieldingly seating tile members and the like and for yieldingly urging such tile members into firm contact with said head.

7. As an article of manufacture, an attaching member for tiling and the like, said attaching member having radiating arms each comprising a base portion for mounting upon a support, said base portions being folded between their sides to form outstanding tenons, said tenons being folded at their outer ends to form flanged heads, and yieldable and angular tile seating wings disposed on opposite margins of said base portions for yieldingly seating tile members and the like and for yieldingly urging such tile members into firm engagement with said heads.

8. As an article of manufacture, an attaching member for mortised tile members and the like, said attaching member having a base portion for attachment to a support, an outstanding tenon on said base portion, a head at the outer end of said tenon, and yieldable oblique wings on said base portion at opposite sides of said tenon for yieldingly seating the mortised tile members and the like and yieldingly pressing said members into engagement with the head of the tenon.

GEORGE H. LENKE.
